UNITED STATES PATENT OFFICE

FRANCIS J. QUINN, OF CHICAGO, ILLINOIS

DESIGN FOR A TRINITY SACRAMENTAL CHEST

Application filed June 20, 1931. Serial No. 40,284. Term of patent 3½ years.

To all whom it may concern:

Be it known that I, FRANCIS J. QUINN, a citizen of the United States, residing at 2000 East 79th St., Chicago, Illinois, have invented a new, original, and ornamental Design for a Trinity Sacramental Chest, of which the following is a specification, reference being had to the accompanying drawing, forming part thereof.

In the drawing:

Fig. 1 is a perspective view of the trinity sacramental chest constituting my design with the doors open showing the interior thereof.

Fig. 2 is a perspective view of the chest, with the doors closed.

The candles and candle holders as shown in Fig. 1 form an integral part of the chest although removable therefrom.

I claim:

The ornamental design for a trinity sacramental chest as shown and described.

FRANCIS J. QUINN.
